CLAIM

The ornamental design for a lens for television camera, as shown and described.

DESCRIPTION

FIG. 1 is a front, left side perspective view of a lens for television camera showing our new design;

FIG. 2 is a bottom, front, right side perspective view thereof;

FIG. 3 is a top, front, right side view thereof;

FIG. 4 is a bottom, front, left side view thereof;

FIG. 5 is a front view thereof;

FIG. 6 is a rear view thereof;

FIG. 7 is a plan view thereof;

FIG. 8 is a bottom view thereof;

FIG. 9 is a left side view thereof; and,

FIG. 10 is a right side view thereof.

The broken lines shown in the drawings depict portions of the lens for television camera that form no part of the claimed design.
